United States Patent Office

Des. 208,854
Patented Oct. 10, 1967

208,854

CART FOR CARRYING REFUSE RECEPTACLES

Oran D. Bratton, Memphis, Tenn., assignor to Mid-America Fabrication Co., a division of Wheel Estate, Inc., Memphis, Tenn.

Filed Jan. 3, 1967, Ser. No. 5,272

Term of patent 14 years

(Cl. D14—3)

FIG. 1

FIG. 2

FIG. 3

FIG. 1 is a perspective view of a cart showing my new design.

FIG. 2 is a top plan view thereof.

FIG. 3 is a side elevational view thereof.

The receptacle shown in broken lines is included for illustrative purposes only.

I claim:

The ornamental design for a cart for carrying refuse receptacles, as shown and described.
